UNITED STATES PATENT OFFICE.

ALLEN D. TOWNE, OF KIRKSVILLE, MISSOURI.

FUSIBLE SAFETY-PLUG FOR BOILERS.

1,150,647.

Specification of Letters Patent.

Patented Aug. 17, 1915.

Application filed May 7, 1914. Serial No. 836,997.

To all whom it may concern:

Be it known that I, ALLEN D. TOWNE, a citizen of the United States, and a resident of Kirksville, in the county of Adair and State of Missouri, have made certain new and useful Improvements in Fusible Safety-Plugs for Boilers, of which the following is a specification.

My invention relates to improvements in fusible safety plugs for boilers, and it consists in the combinations, constructions, and arrangements herein described and claimed.

An object of my invention is to provide a plug which will insure the escape of steam when the water becomes low, even if the plug should be covered over by scale on the interior of the boiler.

A further object of my invention is to provide a plug of the type described having novel means for breaking up the scale so as to permit the heat of the steam to have access to the fusible plug, and to permit the steam to escape freely through the opening caused by the melting of the plug.

25 A further object of my invention is to provide a device of the type described which is simple in construction and which is relatively cheap to manufacture.

Other objects and advantages will appear 30 in the following specification and the novel features of the device will be particularly pointed out in the appended claims.

My invention is illustrated in the accompanying drawings forming part of this application in which—

Figure 1 is a sectional view through the device, and Fig. 2 is a plan view of the plug.

In carrying out my invention I provide 40 a body portion 1 which is threaded as shown at 2, and which has preferably a hexagonal head 3. The threaded portion 2 is designed to enter a threaded opening 4 in the crown sheet 5 of the boiler in the usual manner.

45 The body portion 1 is composed of any suitable metal such as brass. This is provided with a central bore preferably of conical shape arranged to contain a fusible alloy 6 provided with a central conducting rod 7 which extends from the outer end of the fusible member 6 into the body of a charge of explosive material 8, which is carried in a recess in the upper portion of the fusible alloy 6. As will be seen from Fig.

55 1 a nonconducting sheet 9 is disposed immediately above the explosive charge 8

while a plate 10 surmounts the sheet 9. The body portion 1 is undercut at 11 and a cap 12 of alloy forms a further protection for the charge 8.

From the foregoing description of the various parts of the device the operation thereof may be readily understood.

Considerable difficulty is sometimes experienced with boilers whose crown sheets 65 are warped or injured even where the crown sheets are provided with fusible plugs, due to the fact that the scale which forms on the interior of the boiler above the crown sheet will prevent the plug from operating in its 70 usual manner on account of the fact that the scale is not a good conductor of heat, thereby preventing the heat of the steam from reaching the upper end of the fusible plug, and also that it prevents a free passage of 75 steam out of the boiler if the plug should be melted.

Consider now the action when the boiler is incrusted with a layer of scale 13. As soon as the water is lowered sufficiently to 80 leave the crown sheet there is now nothing to convey away the heat which is supplied to the plug. The heat conducting member 7 therefore conveys heat very rapidly to the explosive charge 8, thus causing the latter 85 to quickly reach its ignition temperature. The explosion of this charge blows off the plates 9, 10 and 12 and also the scale above it and permits the now superheated steam to come into contact with the fusible alloy 6. 90 With the fire below it and the superheated steam above it the plug quickly melts and allows the steam to escape downwardly thereby putting out the fire in the usual manner. The crown sheet which might 95 have been injured by too high a temperature is thereby preserved and there is also no danger of an explosion even with a boiler having a considerable quantity of scale disposed above the plug.

100 It will be apparent that the utility of this device lies in the fact that the charge 8 tends to uncover the plug and break up the scale immediately after the water leaves the crown sheet. My invention contemplates 105 any means which is carried by a plug for immediately breaking up the scale so as to permit the superheated steam to have access to the plug while the heat of the fire is at the same time acting from beneath.

I claim:

1. In a fusible plug for boilers, a body

portion, a fusible alloy carried thereby, an explosive charge carried by said fusible alloy at the upper part thereof, and a conductor having one end disposed in said explosive charge and the other end projecting through the bottom of the fusible alloy member.

2. In a fusible plug for boilers, a body portion, a fusible alloy carried thereby, an explosive charge carried by said fusible alloy at the upper part thereof, a conductor having one end disposed in said explosive charge and the other end projecting through the bottom of the fusible alloy member, and

15 a cap surmounting said explosive charge.

3. In a fusible plug for boilers, a body portion threaded exteriorly to enter a threaded opening in the crown sheet of the boiler, said body portion being provided with a tapering bore, a core of fusible metal disposed within said tapering bore, said core having a recess at its top, a charge of explosive material disposed in said recess, a conducting member having one end extend-

ing into said charge, the other end extending downwardly through the core, and a cap disposed above the charge for retaining the latter in position.

4. In a fusible plug for boilers, a body portion threaded exteriorly to enter a threaded opening in the crown sheet of the boiler, said body portion being provided with a tapering bore, a core of fusible metal disposed within said tapering bore, said core having a recess at its top, a charge of explosive material disposed in said recess, a conducting member having one end extending into said charge, the other end extending downwardly through the core, and a cap disposed above the charge for retaining the latter in position, said cap having a nonconducting sheet disposed immediately adjacent to the explosive charge.

ALLEN D. TOWNE.
